UNITED STATES PATENT OFFICE.

ANDREW OPSAL, OF VANCOUVER, BRITISH COLUMBIA, CANADA.

WIRE-ROPE-TRANSMISSION CARRIAGE.

1,106,471.

Specification of Letters Patent. Patented Aug. 11, 1914.

Application filed May 21, 1914. Serial No. 840,057.

To all whom it may concern:

Be it known that I, ANDREW OPSAL, a citizen of the United States, residing at Vancouver, in the Province of British Columbia, Canada, have invented certain new and useful Improvements in Wire-Rope-Transmission Carriages, of which the following is a specification.

This invention relates to the carrier of a wire rope transmission system of that class wherein the load is suspended from a carriage which is movable along an overhead stationary track rope and is drawn along it by a moving wire rope. With this system the suspended load is carried past the guy ropes or supports which sustain the track rope by a pair of star wheels having lateral projections from the arms of the star, from which projections the load is suspended. When a guy rope or track support is encountered by the arms of the star wheels, the star wheel rotates to pass the carriage over it while the load is sustained from the lateral projections of the star wheel arms. With this device, the hauling rope requires to be connected to that portion of the carriage which is above the track rope supports and this hauling rope moving over the supporting guy ropes is destructive of them. Further, as the arms of the star wheels engage the track supports the momentary check causes the load to swing and this swinging movement carries the star wheels with it and frequently interferes with the free entrance of the track rope supports between the arms of the star wheel. It is to overcome these objections that the invention, which is the subject of this application, has been devised: In it, instead of using one pair of star wheels on the track carriage, the carriage is supported on two or more rollers, each having a star wheel on each side of it, and suspended from the lateral projections of these two pair of star wheels is an under-track frame, from the middle of which the load is pivotally suspended. With this arrangement the hauling rope is connected to the under-track part of the carriage, and the load may swing freely on its pivotal connection thereto without disturbing the carriage or interfering with the free action of the star wheel arms. The load is also halved in the amount which is carried by the lateral projections of the star wheels enabling them to rotate more easily.

The invention is particularly described in

the following specification, reference being made to the drawings by which it is accompanied, in which:

Figure 1 is a longitudinal section. Fig. 60 2, a plan, and Fig. 3, a cross section on the line A in Fig. 1.

In these drawings 2 represents the wire rope track and 3 the supports by which it is sustained. These supports 3 are generally 65 connected in wire ropes which are stretched across beneath the line of the track rope between adjacent trees, or between posts or towers where trees are not available. The carriage by which the load is conveyed along 70 this track rope 2 comprises an over-track frame 4 composed of two elongated side plates having between them at each end two or more roller wheels 5, each roller wheel having a star-wheel 6 at each end of it which 75 is independently rotatable on the pin 7 of the roller wheel. The radial arms of these star wheels 6 have shouldered projections 8 which are concentric with the pin on which it rotates. From these shouldered projections 8 an under-track frame 10 is carried, which under-frame is constructed of two lengthwise plates, each having inside its upper edge an inwardly projecting shoe 11 which is curved to the arc of the shouldered 85 projection 8 of the star wheel from which it is carried.

The attachment 14 from which the load is carried is pivotally connected at 12, and the hauling wire rope 13 by which the carriage 90 is moved along the track rope is connected at 15 to each end of the under-track frame 10.

The hauling rope 13 being connected to the under-track frame of the carriage can 95 not wear the track rope supports and the load being pivotally connected to the under frame and its weight carried by two or more pair of star wheels, oscillation of the load does not disturb the carriage or interfere 100 with the free action of the arms of the star wheels in passing over the track rope supports.

I do not desire to be confined to the particular construction of above-track or under-track frame here set forth, nor to the use of star wheels having outward projections from which the under frame is carried, as the same may be varied within a wide range.

Having now particularly described my invention, I hereby declare that what I claim

as new and desire to be protected in by Letters Patent, is:

1. A carriage for an overhead transmission system, said carriage comprising an upper frame having a plurality of roller wheels which bear upon the track rope, each roller wheel having a star wheel on each side of it, each star wheel having outwardly projecting shouldered projections which are concentric with the axis of its roller wheel, and an under-track carriage supported from the shouldered projections of the star wheels and including two side plates, each having projections to coöperate with the projections of the star wheel.

2. A track rope carriage for an overhead transmission system, comprising an upper carriage supported from the track rope on a plurality of rollers, each having a star wheel on each side of it which is independently rotatable on the pin of its roller wheel, each of said star wheels having outwardly projected shouldered projections from its radial arms, the shouldered faces of which are concentric with the axis of its roller wheel, an under-track carriage comprising a pair of side plates having inward projections to engage the shouldered projections of the star wheels, and means for pivotally connecting the load to this under carriage.

3. A carriage for an overhead transmission system, comprising an upper frame composed of two side plates, a roller mounted at each end of the frame on a pin secured in and extending across between the plates, 35 a star wheel rotatably mounted on each end of each roller, the ends of the radial arms of which star wheel are thickened to leave a shoulder which is concentric with the pin, an under-frame composed of two elongated 40 plates secured together the required distance apart each plate having a projection from its upper edge which is curved to an arc corresponding to that of the shouldered projections of the star wheels which star wheel 45 projections are designed to engage the corresponding projections of the under-frame, an attachment to which the load is connected pivotally mounted on a pin extending between the side plates of the under frame, and an attachment at each end of the under frame to which the hauling rope is connected.

In testimony whereof I affix my signature in presence of two witnesses.

ANDREW OPSAL
